UNITED STATES PATENT OFFICE.

FRED W. SCHNEIDER, OF CLAY CENTER, OHIO.

OIL-VAPORIZER.

1,146,208.

Specification of Letters Patent. Patented July 13, 1915.

Application filed February 15, 1915. Serial No. 8,163.

To all whom it may concern:

Be it known that I, FRED W. SCHNEIDER, a citizen of the United States of America, residing at Clay Center, in the county of 5 Ottawa and State of Ohio, have invented certain new and useful Improvements in Oil-Vaporizers, of which the following is a specification, reference being had therein to the accompanying drawings.

10 This invention relates to the vaporization of lubricant particularly heavy oils, and the object of my invention is to provide positive and reliable means, in a manner as hereinafter set forth, for vaporizing or 15 atomizing oils whereby the same can be economically used to insure a thorough lubrication of movable parts.

A further object of this invention is to 20 provide a vaporizing apparatus wherein novel means is employed for causing a lubricating oil to flow in a sinuous or tortuous path whereby it can be repeatedly subjected to the action of steam for vaporizing purposes or to the action of air for atomizing 25 purposes, in either instance, the lubricant being thoroughly disintegrated whereby it may be carried in suspension to the walls of a cylinder or movable parts adapted to be lubricated.

30 I attain the above and other objects by a simple, durable, and inexpensive vaporizing apparatus that will be hereinafter specifically described and then claimed, and reference will now be had to the drawing, where- 35 in—

Figure 1 is a vertical cross sectional view of the apparatus, and Figs. 2 and 3 are vertical transverse sectional views of the same, looking in opposite directions.

40 An apparatus in accordance with this invention comprises a rectangular or oblong casing 1. The top of the casing is provided with a steam supply pipe 2 and the bottom of the casing with a steam and lubricant out- 45 let pipe 3 adapted to extend to a cylinder or part to be lubricated (not shown.) A wall 4 of the casing has the inner side thereof provided with inclined trays or troughs 5 and 6, the trays 5 being inclined the reverse of the trays 6 and staggered with relation to 50 said trays, whereby lubricating oil deposited in the uppermost tray gradually flows from one tray to another and traverses a sinuous or tortuous passage before reaching the bot- 55 tom of the casing. With the trays 5 and 6

of considerable length and at a slight inclination considerable time is consumed in lubricant flowing from the upper end of the casing to the lower end thereof, and it is during this period of time that the lubricant 60 is subjected to the action of steam and vaporized.

Lubricant is admitted to the uppermost tray 5 through the medium of a supply pipe 7 at the upper end of the wall 4 and as steam 65 enters the casing from the pipe 2, the steam impinges the lubricant upon the trays, also inclined deflectors 8, carried by the inner side of a wall 9 of the casing. The deflectors 8 as shown in Fig. 3, are the same width as 70 the wall 9 and by reference to Fig. 1, it will be observed that the deflectors vary in length. This is in order that steam may impinge each deflector and the steam be directed toward the inclined trays 5 and 6. 75 By contacting with the lubricant in the trays, the steam becomes saturated with the lubricant and carries the same into suspension to the cylinder receiving the steam. This vaporization of the lubricant continues 80 as long as steam and lubricant are admitted to the casing and since the action is automatic, the apparatus only needs attention for cleaning purposes. By regulating the admission of steam, oil or other lubricant 85 to the uppermost tray 5, the lubricant is caused to flow in a very thin film over the trays. The steam being brought into direct contact with this thin layer of lubricant will quickly and thoroughly vaporize it and 90 when carried into a cylinder by the steam, it is equally distributed upon the walls of the cylinder, thus insuring a thorough lubrication without one part of the cylinder being 95 lubricated more than another part.

One embodiment of my invention has been illustrated, but it is to be understood that the structural elements are susceptible to such variations and modifications as fall within the scope of the appended claims.

What I claim is:

1. A vaporizing apparatus comprising a casing having the top thereof provided with a steam inlet and the bottom thereof with a steam outlet, a lubricant supply pipe in communication with the top of said casing at one side thereof, staggeredly arranged inclined trays carried by the same side of said casing and adapted to receive lubricant from the supply pipe thereof, and means at the 105 110

opposite side of said casing adapted to deflect steam onto said trays to vaporize the lubricant flowing thereon.

2. A vaporizing apparatus comprising a casing adapted to receive steam and a lubricant, staggeredly arranged trays at one side of said casing adapted to receive lubricant and cause the same to flow in a thin film, and means for deflecting steam on to said trays to vaporize lubricant thereon.

3. A vaporizing apparatus comprising a casing having the top thereof provided with a steam inlet and the bottom thereof with a steam outlet, a lubricant supply pipe in communication with the upper end of said

casing at one side thereof, inclined staggeredly arranged trays carried by the same side of said casing and adapted to receive lubricant from said supply pipe and cause the same to travel in a thin film to the bottom 20 of said casing, and inclined deflectors carried by the opposite wall of said casing and adapted to deflect steam on to said trays to vaporize the lubricant thereon.

In testimony whereof I affix my signature 25 in presence of two witnesses.

FRED W. SCHNEIDER.
